(57) CLAIM

The ornamental design for a meat mincer, as shown and described.

DESCRIPTION

1. Meat mincer

1.1 is a front and right side perspective view showing the meat mincer of my design;

1.2 is a right side elevation view thereof;

1.3 is a left side elevation view thereof;

1.4 is a front elevation view thereof;

1.5 is a back elevation view thereof;

1.6 is a top plan view thereof; and

1.7 is a bottom plan view thereof.

The broken lines showing portions of the meat mincer form no part of the claimed design.
